CLAIM

The ornamental design for a tumbler, as shown and described.

DESCRIPTION

FIG. 1 is a top, perspective view showing a first embodiment of my new design for a tumbler.

FIG. 2 is a bottom, perspective view of FIG. 1.

FIG. 3 is a front side elevation view of FIG. 1.

FIG. 4 is a rear side elevation view of FIG. 1.

FIG. 5 is a left side elevation view of FIG. 1.

FIG. 6 is a right side elevation view of FIG. 1.

FIG. 7 is a top view of FIG. 1.

FIG. 8 is a bottom view of FIG. 1; and,

FIG. 9 is a side view of a second embodiment of my tumbler.

1 Claim, 8 Drawing Sheets(56)
